UNITED STATES PATENT OFFICE.

ROY H. OLSEN, OF HAMMOND, INDIANA, ASSIGNOR TO STRAUBE PIANO COMPANY, OF HAMMOND, INDIANA, A CORPORATION OF INDIANA.

TONE-MODULATING DEVICE FOR PIANOS.

1,205,561.

Specification of Letters Patent.

Patented Nov. 21, 1916.

Application filed June 1, 1915. Serial No. 31,402.

To all whom it may concern:

Be it known that I, Roy H. OLSEN, a citizen of the United States, and resident of Hammond, in the county of Lake and State 5 of Indiana, have invented certain new and useful Improvements in Tone-Modulating Devices for Pianos, of which the following is a specification.

This invention relates to a tone modulating device for pianos, particularly adapted for use in player pianos, although not necessarily limited to such use.

It is the object of my invention to provide a mechanism, whereby the tones of a piano 15 may be modulated to produce tones of a quality closely resembling those of a harp.

A further object of my invention is the provision of a tone modulating device for pianos, which may be constructed of a minimum 20 number of simple and relatively inexpensive parts and which may be controlled by either the hands or feet of the operator at will.

Other objects and advantages of my invention will be apparent as it is better understood by reference to the following specification when read in connection with the accompanying drawing, in which—

Figure 1 is a vertical section through the 25 piano showing the modulating device installed; Fig. 2 is a front elevation of a piano with the front broken away to show the arrangement of the tone modulating device; Fig. 3 is an enlarged detail of the 30 pneumatic with the valve chamber in section; Fig. 4 is a similar detail with the valve chamber sectioned in a plane normal to the plane of Fig. 3; and Fig. 5 is a detail in section of the keyboard-controlling mechanism.

Referring to the drawings, 1 indicates the casing of a piano, carrying the usual means 2 for supporting the strings 3 in proper relation to the sounding board 4. Pivoted 45 mounted at 5 are the usual action-hammers 6.

Pivoted at 7 to the end walls of the casing 1 are the arms 8 supporting a longitudinally extending bar 9 to which one edge 50 of a sheet 10 of felt or other suitable material is secured. The other edge of the sheet 10 is slotted to produce a plurality of depending fingers 11 spaced to correspond exactly with the spacing of the strings corresponding to individual tones and provided

at their extremities with metallic buttons 12. The buttons 12 are adapted to be disposed between the hammers 6 and the strings 3 and to transfer the force of the hammer blow to the strings. The interposition of the metallic buttons between the hammers and the strings results in a peculiar tone quality which closely resembles the tone of a harp. Springs 13, secured to arms 8 and to pins 14 in the end walls of 65 the casing 1, normally maintain the arms 8 and the bar 9 in raised position so that the buttons 12 are outside the path of the hammers 6.

A tension rod 15 is pivotally secured at 70 the upper end to the bar 9 and loosely engages at its lower end the lever 16 pivoted in a pair of brackets 17 at the base of the piano and connected to a pedal pivoted in a bracket 19 disposed midway of the base. 75 By actuating the pedal 18 the lever 16 will be actuated to draw the rod 15 and the bar 9 downwardly to position the metallic buttons 12 in contact with the strings 3 and in the path of the hammers 6.

In order that the tone modulating device may be operated from the keyboard of a piano I provide a pneumatic 20, suitably mounted within the casing 1 and loosely connected to the rod 15 at 21. A valve casing 22 adjacent the pneumatic 20 is divided into two chambers by a diaphragm 23, the upper chamber being connected by a duct 24 with a suction bellows 25, disposed within the casing 1 adjacent the base thereof and operable by means of pedals 26 to produce a partial vacuum in the duct 24 and the upper chamber of the valve casing 23. The lower chamber of the casing 22 is connected by a duct 27 to an outlet in the 95 underside of the keyboard which is normally closed by a leaf spring 28. A push rod 29 extends through the keyboard and is provided with a button 30 whereby the spring 28 may be depressed to open the outlet from the duct 27. The vacuum maintained in the upper chamber of the valve casing 22 is communicated to the lower chamber and the duct 27 by a bleeder 31 of small diameter in the diaphragm 23.

Supported on the diaphragm 23 are the valve stems 32 carrying valves 33 and 34 and the former being adapted to close the passage from the upper chamber of the valve casing 22 to the pneumatic 20 and the 110

latter being adapted to close the air vent 35 to the pneumatic 20. Normally the valve 33 is seated and the valve 34 is open, the pneumatic being held in distended position by the springs 13 operating through arms 8, bar 9 and rod 15. When the push rod 29 is operated to depress the spring 28 the vacuum in the duct 27 and the lower chamber of the valve casing 22 is overcome and the diaphragm 23 is forced upwardly by the air pressure in the lower chamber, thereby lifting the valve stems 32, unseating valve 33 and seating valve 34. The passage from the pneumatic 20 to the upper chamber of the valve casing 22 is thus opened and consequently the pneumatic 20 is deflated and draws the rod 3 downwardly, moving the bar 9 to position the buttons 12 in front of the individual strings.

It will be readily understood from the foregoing that I have perfected a mechanism, whereby tones of different quality than those ordinarily produced by pianos result from the simple expedient of introducing a metallic member between the strings and the hammers and that I have also provided means whereby the modulating device may be controlled either from the keyboard of the piano or by means of a pedal. It will be apparent that, if the device is applied to a self-playing piano, it will be desirable, when the instrument is played automatically, to control the modulating device from the keyboard, since the operator maintains the piano in operation by means of the pedals. On the other hand

if the instrument is manually played it will be necessary to use the pedal 13, since the operator's hands are engaged.

It will be apparent that various changes may be made in the form, construction and arrangement of the parts without departing from the spirit and scope of the invention or sacrificing any of its material advantages, the form hereinbefore described being merely a preferred embodiment thereof.

I claim:

In a device of the character described, the combination of a plurality of strings, a plurality of hammers, a swinging frame, resilient means to normally maintain said frame in raised position, metallic means suspended from said frame, means for swinging said frame and moving said metallic means into the path of said hammers, including a tension rod connected to said frame, a pneumatic, an abutment on said tension rod, means on said pneumatic engaging said abutment, whereby said rod may be actuated by said pneumatic but is free therefrom when otherwise actuated, means for controlling said pneumatic, a pivoted lever connected to said tension rod, and a pivoted pedal connected to said lever, whereby said frame is depressed when said pedal is actuated.

ROY H. OLSEN.
